UNITED STATES PATENT OFFICE.

AUGUST ZACHARIAS, OF MINNEAPOLIS, MINNESOTA.

AUXILIARY HEATER.

1,332,371.

Specification of Letters Patent.

Patented Mar. 2, 1920.

Application filed October 10, 1918. Serial No. 257,627.

To all whom it may concern:

Be it known that I, AUGUST ZACHARIAS, a citizen of the United States, residing at Minneapolis, in the county of Hennepin and 5 State of Minnesota, have invented certain new and useful Improvements in Auxiliary Heaters; and I do hereby declare the following to be a full, clear, and exact description of the invention, such as will enable 10 others skilled in the art to which it appertains to make and use the same.

My invention has for its object to provide a simple and highly efficient auxiliary heater and soot collector for use in connection with 15 stoves, furnaces and other heat producing plants. Generally stated, the invention consists of the novel devices and combinations of devices hereinafter described and defined in the claims.

20 It is a well known fact that there is generally very great waste in heat due to the unnecessary escape of hot flames or other gases in the flues or smoke stacks. My invention provides an auxiliary heater which, 25 when connected between the stove or furnace and the flue or smoke stack, will, without destroying the draft, accomplish two important results, to wit, it will absorb and radiate a large amount of heat that would 30 otherwise be wasted and it will precipitate and collect the soot or solid matter carried in the smoke and will thus purify the smoke and substantially eliminate the smoke nuisance.

35 The invention is illustrated in the accompanying drawings wherein like characters indicate like parts throughout the several views. Referring to the drawings,

Figure 1 is a side elevation of the improved heater;

Fig. 2 is a vertical section taken on the line 2--2 of Fig. 1;

Fig. 3 is a vertical section taken on the line 3--3 of Fig. 2; and

45 Fig. 4 is a view corresponding to Fig. 3, but showing the heater provided with an exterior jacket and certain air circulating tubes.

Considering first the construction illustrated in Figs. 1, 2 and 3, the numeral 5 indicates an upright main shell of sheet metal, preferably of cylindrical form, but possibly of angular cross section. This main drum is provided with upper and 55 lower heads and above its lower head with a false bottom 6 that affords a lower air

intake chamber 7. Extended diametrically through the upper portion of the drum 5 is a large air tube 8 that is open at both ends. Extended diametrically through the drum 60 at a point considerably lower down than the tube 8 and at a right angle to the said tube 8 is another air tube 9, the outer ends of which are closed by heads 10. The central portion of the tube 9 is connected to the 65 central portion of the flue 8 by a short upright air flue 11.

Located on the false bottom 6 and removable through one side of the drum 5 is a soot receptacle or box 12 into which the 70 soot is directed by a conical hopper 13 supported within the drum above said box and having its upper edge rigidly secured to the interior of said drum. Cold air flues 14, as shown, two in number and located at 75 diametrically opposite points, in respect to the axis of the drum, are extended through the false bottom 6, up through the hopper 13 and into the lower portion of the lower diametrical air flue 9.

80 Cold air from the room is adapted to be drawn into the air chamber 7, through lateral air intake ports which, as shown, are controlled by dampers 15. Cold fresh air from the exterior of the building or elsewhere 85 is adapted to be drawn into the said air chamber 7 through one or more so-called fresh air intake pipes 16 equipped with dampers 17, by means of which the said pipes may be closed or open to any desired 90 extent.

The hot flames or products of combustion from the stove, furnace, or other heater are conveyed by a so-called smoke pipe 18 that opens through one side of the drum 5, preferably in horizontal line with the lower diametrical tube 9. A horizontal baffle plate 19 is attached to the drum 5 and to the top of said tube 9 and prevents the flames or smoke delivered into the drum from the 100 pipe 18 from passing directly upward and causes the same to take a downward course under the said tube 9. The smoke and other gases are carried from the top of the drum 5 through a smoke pipe 20.

105 The operation of the auxiliary heater described is substantially as follows:

The smoke and other gases entering the drum from the smoke pipe 18, as already stated, will be deflected downward under 110 and around the lower diametrical air tube 9, and from thence, will pass upward against

and around the upright flue 11 and upper diametrical tube 8. In this way, the other flames or gases are brought into contact with a very large amount of metallic heat absorbing surface so that the air contained within the said tubes 8, 9 and 11 will be very much heated.

As the smoke or other products pass under the tube 9, they enter a chamber that has relatively very large capacity and hence, their movement will be very much slowed up while they are at the same time making an upward turn. This will cause precipitation of the soot into the hopper 13 and this precipitation is further produced by the fact that the air in the lower part of the drum is relatively cool, which, in itself, increases the tendency toward precipitation of the soot. Here it is important to note that cold air in passing upward through the flues 14 will tend to keep the lower portion of the air chamber within the drum 5 at low temperature. Of course, the dust precipitating into the hopper 13 will be caught by the dust box or receptacle 12, and from time to time may be removed.

By manipulation of the dampers 15 and 17, the relative amounts of air drawn directly from the room close to the floor and from the exterior of the building, or elsewhere through pipes 16, may be proportioned in any desired way. All of the cold air entering the chamber 7 will be drawn upward through the flues 14 and into the lower air tube 9. From the air tube 9, the air which has been partly heated in its passage upward through the flues 14 will be further heated as it passes on upward through the flues 11 and 8 and will be discharged outward into the room through the open ends of the flue 8. This arrangement gives a highly efficient auxiliary heater, as well as a soot precipitator and smoke purifier.

45 The construction illustrated in Fig. 4 is, or may be like, or substantially like that illustrated in Figs. 1, 2 and 3 with the addition thereto of an outer jacket 21 which is placed around the upper portion of the drum but terminates at its lower portion, preferably about in line with the upper portion of the hopper 13. This jacket 21 affords an air chamber 22 around and over the top of the upper portion of the drum. This jacket 21, at its lower portion, is provided with air intake pipes 23 that may be short, as illustrated in Fig. 4, or may be extended from a distant point. These pipes 23 will preferably be provided with dampers 24. Air drawn in through the pipes 23 and heated in the chamber 22 may be discharged through hot air delivery pipes 25 which may lead to different rooms or any suitable point of delivery. Also, in this arrangement, the hot air discharged from the open ends of up-

per tube 8, instead of passing directly into the room, will pass first into the air chamber 22 and thence out through the hot air pipes 25 either into the same room or in some other place of delivery.

70

What I claim is:

1. In a heater, the combination with an upright drum having smoke inlet and outlet pipes, of a transverse air tube extended through said drum, a hopper in the lower portion of said drum, and air intake tubes extending within said drum upward through said hopper and connected to said air tube, said air intake tubes being open at their lower ends for drawing air from a point near the floor.

2. In an auxiliary heater, the combination with an upright drum having smoke inlet and outlet pipes, of approximately diametrical air tubes extended through said drum, one above the other and at an angle, one with the other, an upright air tube centrally connecting said diametrical air tubes, the said upper diametrical tube having open ends, the smoke intake pipe of said drum being arranged to deliver the hot gases against said lower diametrical tube, a hopper in the lower portion of said drum, and air intake tubes extended within said drum upward through said hopper and leading to said lower diametrical air tube.

3. In an auxiliary heater, the combination with an upright drum having smoke inlet and outlet pipes, of approximately diametrical air tubes extended through said drum, one above the other and at an angle, one with the other, an upright air tube centrally connecting said diametrical air tubes, the said upper diametrical tube having open ends, the smoke intake pipe of said drum being arranged to deliver the hot gases against said lower diametrical tube, a hopper in the lower portion of said drum, air intake tubes extended within said drum upward through said hopper and leading to said lower diametrical air tube.

115

4. In an auxiliary heater, the combination with an upright drum having smoke inlet and outlet pipes, of approximately diametrical air tubes extended through said drum, one above the other and at an angle, one with the other, an upright air tube centrally connecting said diametrical air tubes, the said upper diametrical tube having open ends, the smoke intake pipe of said drum being arranged to deliver the hot gases against said lower diametrical tube, a hopper in the lower portion of said drum, an air chamber in the bottom of said drum below said hopper, upright air tubes within said drum extended upward from said lower air

120

130

chamber through said hopper and connected to said diametrical tube, and air supply ducts opening into said lower air chamber.

5. In an auxiliary heater, the combination with an upright drum having smoke inlet and outlet pipes, of approximately diametrical air tubes extended through said drum, one above the other and at an angle, one with the other, an upright air tube centrally connecting said diametrical air tubes, the said upper diametrical tube having open ends, the smoke intake pipe of said drum being arranged to deliver the hot gases against said lower diametrical tube, a hopper in the

lower portion of said drum, an air chamber 15 in the bottom of said drum below said hopper, upright air tubes within said drum extended upward from said lower air chamber through said hopper and connected to said diametrical tube, and independent damper 20 controlled air ducts opening into said lower air chamber.

In testimony whereof I affix my signature in presence of two witnesses.

AUGUST ZACHARIAS.
